UNITED STATES PATENT OFFICE.

ADOLPH A. CAILLE, OF DETROIT, MICHIGAN, ASSIGNOR TO THE
CAILLE-SCHIEMER COMPANY, OF SAME PLACE.

DESIGN FOR A GAME-BOARD.

SPECIFICATION forming part of Design No. 34,231, dated March 12, 1901.

Application filed February 4, 1901. Serial No. 46,033. Term of patent 7 years.

To all whom it may concern:

Be it known that I, ADOLPH A. CAILLE, a citizen of the United States, residing at Detroit, in the county of Wayne and State of Michigan, have invented and produced a certain new and original Design for a Game-Board, of which the following is a specification, reference being had therein to the accompanying drawings, in which—

Figure 1 is a perspective view of the game-board embodying my invention, and Fig. 2 is a side elevation thereof.

The reference-letter A designates the board proper, oblong in configuration and having a squared end B, provided with a raised edge portion C and enlarged corners D and E. As shown, these corners are in the form of flat rectangular panels arranged in the same plane with the edge portion C and projecting beyond the sides of the board proper. The opposite or outer end F of the said board is rounded, as illustrated, and is provided with an upwardly-projecting flange G, extending about the edge of the board and terminating abruptly in shoulders G' below the enlarged corners, as plainly shown.

H and H' designate ornamental brackets in the same horizontal plane as the panels which connect the outer corners I thereof with the flange G.

J and J' designate ribs projecting forwardly from the inner portions of the enlarged corners and spaced from the flange G, as shown.

K designates a series of smaller ribs spaced from each other and projecting forward from the raised edge C, as shown. 35

The forward end of the board is supported by a single curved leg L, while the inner or squared portion of the board is supported by similar legs M of less length than the single 40 support referred to and depending from the enlarged corners, as illustrated.

O represents a series of apertures in the board proper, arranged in the shape of a diamond, and P designates a leg depending from 45 a central portion of the raised rib and hollowed out to form a pocket, as plainly shown.

The essential feature of the invention consists of the rounded outer or forward board end and a squared inner end provided with 50 enlarged corners in the form of flat rectangular panels, the ornamental scrollwork connecting the corners to the board proper and the curved supporting-legs arranged beneath the outer board end and the enlarged corners, as shown. 55

What I claim as my invention is—

The design for a game-board, substantially as herein shown and described.

In testimony whereof I affix my signature 60 in presence of two witnesses.

ADOLPH A. CAILLE.
